US0D1032142S

(12) **United States Design Patent** (10) Patent No.: **US D1,032,142 S**
(45) Date of Patent: ** Jun. 25, 2024

(54) **CONFECTION**

(71) Applicant: **Cadbury UK Limited**, Birmingham (GB)

(72) Inventors: **Manisha Koner**, Birmingham (GB); **Ricardo Carvajal**, Birmingham (GB)

(73) Assignee: **CADBURY UK LIMITED**, Birmingham (GB)

(**) Term: **15 Years**

(21) Appl. No.: **29/922,560**

(22) Filed: **Dec. 22, 2023**

Primary Examiner — Katie Jane Stofko

(74) *Attorney, Agent, or Firm* — CANTOR COLBURN LLP

(57) **CLAIM**

We claim, the ornamental design for a confection, as shown and described.

DESCRIPTION

FIG. 1 is a front, top and right side perspective view of a confection, showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken line disclosure forms no part of the claimed design.

1 Claim, 5 Drawing Sheets
